(No Model.)

L. J. ATWOOD.
EXPANSIBLE RING FOR LAMP SUPPORTS.

No. 521,073.

Patented June 5, 1894.

UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

EXPANSIBLE RING FOR LAMP-SUPPORTS.

SPECIFICATION forming part of Letters Patent No. 521,073, dated June 5, 1894.

Application filed November 9, 1893. Serial No. 490,432. (No model.)

To all whom it may concern:

Be it known that I, LEWIS J. ATWOOD, a citizen of the United States, residing at Waterbury, in the county of New Haven and 5 State of Connecticut, have invented an Improvement in Expansible Rings for Lamp-Supports, of which the following is a specification.

Lamps have heretofore been suspended by 10 a ring at the bottom of a hanger or harp and such ring has also been supported by a bracket or arm, and these rings have been expansible so as to be opened for the insertion of a lamp from below and brought together around the 15 lamp and held in the closed position by the action of a hook.

My present invention is made to facilitate the construction of the parts and also the operating of the same by one hand while the 20 lamp is being held by the other hand, and my invention relates to the combination of devices hereinafter set forth.

In the drawings, Figure 1 is a side view of the ring in its closed or contracted position. 25 Fig. 2 is a similar view of the ring as open. Fig. 3 is a plan view of the ring in the position shown in Fig. 2, and Fig. 4 is a section in larger size at the line $\alpha\alpha$ of Fig. 2.

The ring A is of suitable material such as 30 band metal and of the proper size to pass around the lamp, and the ring is either connected with a bracket or more usually provided with ears B for the suspending wires or harp C, and the length of the ring or band A is sufficient for the ends to lap one on the 35 other and be slotted, as at 2, 3, there being rivets or studs 4, 5 near the respective ends of the ring passing through the slots in the other portion of the ring; and it is advantageous to employ spring metal that will cause 40 the ring to expand when not otherwise held, so that the respective studs 4 and 5 will be at the respective ends of the slots 2 and 3 when the ring is not otherwise acted upon, so that 45 the ring will expand to liberate the lamp and will be retracted in closing the ring around the lamp.

I make use of the swinging latch D which is pivoted at 6 to that end of the ring A which 50 is outside the other end of the ring, so that

this latch D is easy of access, and it is provided with a thumb-piece 7 and a hooking end 8 adapted to catch over the stud 9 and hold the ring when in a closed condition; and I provide a stop finger 10 in the form of a 55 tongue pressed back in the sheet metal of the latch near the pivot thereof and passing into an opening in the ring A near the end of one of the slots 2. This stop finger allows for the necessary movement of the swinging latch 60 as the same may be moved to latch or unlatch the same from the stud 9, but this stop finger prevents the swinging latch dropping down too far when the ring A is open. I remark that I have shown the pivot 6 for the 65 swinging latch D as formed by one end of the stud 5, but the same may be a separate pivot if desired.

By the construction aforesaid the ring A may be left open when the lamp is not supported thereby, so that the lamp may be passed up from below into the ring A and when in the proper position the ring may be closed by the thumb and finger of one hand acting between the thumb-piece 7 of the swinging latch 70 D and one of the ears B, and in drawing the latch along so as to contract the ring, the hook 8 of the swinging latch is caused to pass over the stud 9 and catch behind the same and thereby secure the ring in its contracted 75 position in the most reliable manner. By the reverse movement the latch is liberated and the ring expands so that the lamp can be taken out from the same. If desired only the slot 3 may be employed, the slot 2 and the stud 4 80 being dispensed with. The ear B that is adjacent to the latch becomes a finger piece for the finger or thumb to rest against while the other member of the hand acts on the latch, but I do not limit myself to the form or character 85 of this finger piece.

I claim as my invention—

1. The combination with the expansible spring ring A having a slot 3 and stud 5 in the slot, of the swinging latch D pivoted near one 90 end of the ring and having a hook and a thumb-piece, the stud 9 upon the ring near its other end and over which the hook catches, and a stop finger 10 formed of the metal of the 95 swinging latch pressed back into an opening 100

in the ring to limit the movement of the latch when the ring is open, substantially as set forth.

2. The combination with the expandible
5 spring ring A. having slots 2. and 3. and studs
4. and 5. in the respective slots, of the swing-
ing latch D. pivoted near one end of the ring
and having a hook and a thumb-piece, the
stud 9. upon the ring over which the hook
10 catches, and a stop-finger to limit the move-

ment of the latch when the ring is open, and
a finger piece for the hand to act against in
operating the latch and spring ring, substan-
tially as set forth.

Signed by me this 1st day of November, 15
1893.

LEWIS J. ATWOOD.
